UNITED STATES PATENT OFFICE.

EMIL GUTMANN, OF NEW YORK, N. Y.

DESIGN FOR A PACKING-BOX FOR GARTERS.

SPECIFICATION forming part of Design No. 31,586, dated October 3, 1899.

Application filed August 30, 1899. Serial No. 729,015. Term of patent 7 years.

To all whom it may concern:

Be it known that I, EMIL GUTMANN, a citizen of the United States, and a resident of the city of New York, borough of Manhattan, State of New York, have invented and produced a new and original Design for a Packing-Box for Garters, of which the following is a specification, reference being had to the accompanying drawings, forming a part thereof.

10 The essential feature of my design consists in a packing-box for garters, the side of which is embellished by the representation of a pair of lower limbs in the position which they would assume when the person is standing, 15 the said limbs being crossed by bands just below the knee portions and covered by an edging of embroidery at the knee portion.

In the accompanying drawings, Figure 1 is a top plan view of the box, and Fig. 2 is a 20 transverse section in the plane of line 2 2 of Fig. 1.

The box is denoted by A, its embellished side by a, the lower limbs, which are here represented as made intaglio, by B B', the bands across the limbs below the knee, in the 25 position which garters would occupy, by b b', and the ornamental edging across the limbs at the knee portion by C C'.

What I claim is:—

The design for a packing-box for garters, 30 substantially as herein shown and described.

In testimony that I claim the foregoing as my invention I have signed my name, in presence of two witnesses, this 25th day of August, 1899.

EMIL GUTMANN.
